(57) CLAIM

The ornamental design for a cup holder for handle bars, as shown and described.

DESCRIPTION

FIG. 1 is a top plan view showing my new design for a cup holder for handle bars;

FIG. 2 is a right side elevational view;

FIG. 3 is a bottom plan view;

FIG. 4 is a front elevational view;

FIG. 5 is a rear elevational view; and

FIG. 6 is a left side elevational view; and,

FIG. 7 is a perspective view showing the holder with a cup mounted on a handle bar.

The broken line drawings of the handle bar and cup are for illustrative purposes only and form no part of the claimed design.
